CLAIM

The ornamental design for a combined toilet seat cover and infant's seat, as shown and described.

DESCRIPTION

FIG. 1 is a perspective view of a combined toilet seat cover and infant's seat showing my new design with cover in a raised position;

FIG. 2 is a rear elevational view thereof with both the cover and seat in a lowered position;

FIG. 3 is a right side elevational view of FIG. 1;

FIG. 4 is a top plan view of FIG. 2; and,

FIG. 5 is a bottom plan view of FIG. 2.

The broken line representation of a toilet seat and the fragmentary broken line showing of a toilet in FIG. 3 is for purposes of illustration only and forms no part of the claimed design.
